UNITED STATES PATENT OFFICE

2,625,974

BILLFOLD HAVING AN EXPANSIBLE POCKET

Douglas J. Broughton, Springfield, Mass., assignor
to Buxton, Incorporated, Springfield, Mass., a
corporation of Massachusetts

Application September 2, 1949, Serial No. 113,760

2 Claims. (Cl. 150—38)

1

This invention relates to an improvement in billfolds, more particularly to an expandable pocket construction for billfolds.

The principal object of the invention is to provide a construction and an arrangement of the parts forming a pocket which while permitting a substantial degree of expansion and contraction does not add materially to the thickness of the billfold. The invention is of particular advantage in the construction of light and thin billfolds, but it may be used to advantage in larger folds of the carry-all type.

In the accompanying drawing, which illustrates a billfold embodying the invention,

Fig. 1 is an elevational view of the billfold in open position;

Fig. 2 is a detailed view of the outer front wall pocket members in partially assembled position;

Fig. 3 is a detailed view of the intermediate wall member;

Fig. 4 is a detailed view showing the elements of Figs. 2 and 3 in assembled position; and

Fig. 5 is a fragmentary detailed view showing the assembly of Fig. 4 in position to be incorporated with the other elements of the billfold.

Referring to the drawings, the billfold generally indicated at 1 is shown as comprising a rear wall member 2 provided with narrow end extensions 3 and 4 and narrow bottom extension 5. The front wall is shown as comprising end sections generally indicated at 6 and 7 spaced from each other and from the central fold line of the billfold indicated at 8. The end section 7 comprises an inner front wall member 9, two outer front wall members 10 and 11 and an intermediate wall member 12. Wall members 9 and 10 can obviously be formed in one piece but preferably and as shown, the outer front wall member 10 is formed with an attaching portion 13 which is stitched to the upper edge of the inner wall member 9, as at 14, and is provided with a crease line 15 about which the member 10 may be folded, the portion 13 forming part of the inner wall. The second outer wall member 11 may also be formed integral with member 9, or have an integral connection with extension 5, but preferably and as shown is formed as a separate piece. Members 10 and 11 are made somewhat less in width than half the transverse width of the wall member 9—13 so that when member 11 is positioned on the wall member 9 with its lower edge coinciding with the lower edge of member 9 as shown in Fig. 2, and wall member 10 is folded downwardly along fold line 15 the adjacent edges of 10 and 11 are slightly spaced from each other, as shown in Figs. 1, 4 and 5.

2

Intermediate member 12 can be integrally connected to extension 4 but preferably and as shown is a separate piece. Member 12 has a length slightly greater than the over-all length of wall members 9, 10 and 11 and a transverse width slightly less than the wall member 9 plus the portion 13 above the attaching portion 14. Preferably member 12 is formed of slightly stiffer leather than members 10 and 11 or is reinforced to give it additional stiffness. The intermediate wall member 12 is provided adjacent its outer end with an arcuate slot 17. The wall members 10 and 11 are cut back from their end edges as at 18 and 19 to form tongues 20 and 21.

The intermediate wall member 12 is inserted between the outer wall members 10 and 11 and the inner wall member 9 as shown in Fig. 4, and the tongues 20 and 21 which when the parts are assembled extend from the adjacent outer end corners of members 10 and 11, are inserted through the slot 17 as shown in the latter figure. The assembly of the inner, outer and intermediate wall members, as shown in Fig. 4, is positioned against the end section of the rear wall member 2 as shown in Fig. 5, and the end extension 4 of the rear wall member is folded over on the end edge portion of the inner wall member 9, intermediate wall member 12 and the ends of the tongues 20 and 21, while the edge extension 5 is folded over on the lower edge portions of members 9 and 11. A line of stitching 22 is run through the folded over extensions 4 and 5 and the various parts underlying said extensions to secure the parts together.

The end section 6 may be formed in a similar manner as desired, but as shown is constructed by folding over a single piece of material along a line 23 to form inner and outer wall portions 24 and 25, the latter portion being provided with a window opening 26 closed in the usual manner by a transparent window 27. The outer end edge portions of the walls 24 and 25 are inserted beneath the overfolded end extension 3 of the adjacent rear wall portion, and the bottom edge of members 24 and 25, or of member 25 at least, is inserted beneath the bottom extension 5, to be included in the line of stitching 22.

A bridging member 28 has one end portion inserted between the wall members 24—25 and the other end portion inserted between the rear wall member 9 and the intermediate wall member 12. The end portions of the bridging member 28 may be interlocked or otherwise secured to the wall members 24 and 9 respectively in any suitable manner not shown.

55 By the construction above described a pocket

29 is formed between bridging member **28** and intermediate member **12** which is capable of substantial expansion. As above mentioned wall member **12** is slightly narrower than wall member **9** and as pocket **29** is stuffed the wall members **10** and **11** yield and separate slightly by distortion of the relatively long tongues **21** and **20** and the outward movement of the latter toward the ends of slot **17**, permitting the wall member **12** to swing away from member **28**. Flexible pocket capacity is also provided between members **10**—**11**.

What I claim is:

1. In a billfold having front and rear wall members, said front wall member comprising spaced end sections, at least one of said sections including an inner wall member connected at its outer end to the adjacent end of the rear wall and connected at its bottom to the bottom of the rear wall, an intermediate wall member overlying said inner wall member and connected at its outer end only to the adjacent end of the rear wall, an outer wall member connected at its top to the top of the inner wall and extending downwardly partway over the intermediate wall, a second outer wall member connected at its bottom to the bottom of the rear wall and extending upwardly partway over the intermediate wall, means connecting the adjacent outer corners of said outer wall members to the adjacent end of the rear wall, and a bridging member extending between said sections, one end of said bridging member extending between the inner wall member and the intermediate member.

2. In a billfold having front and rear wall members, said front wall member comprising spaced end sections, at least one of said sections including an inner, an intermediate and two outer wall members, the intermediate member being connected to and extending inwardly from

5 the end of the rear wall member over the inner wall member, one of said outer wall members being connected to and extending downwardly from the upper edge of the inner wall member partway over the intermediate member, the other of said outer wall members being connected to and extending upwardly from the lower edge of the rear wall member partway over the intermediate member, tongues extending from the adjacent outer end corners of the outer wall members, said intermediate member being formed with a transverse slot, closely adjacent its outer end, through which said tongues extend, means to hold said tongues in said slot, and a bridging member extending between said sections, one end of said bridging member extending between the inner wall member and said intermediate wall member.
